Primary Examiner — Daniel J Domino*Assistant Examiner* — Samina Vieth(74) *Attorney, Agent, or Firm* — Lee & Hayes, P.C.**CLAIM**

The ornamental design for a vehicle antenna, as shown and described.

DESCRIPTION

FIG. 1 is a front perspective view of a vehicle antenna;

FIG. 2 is a front view thereof;

FIG. 3 is a back view thereof;

FIG. 4 is a right-side view thereof;

FIG. 5 is a left-side view thereof;

FIG. 6 is a top view thereof;

FIG. 7 is a bottom view thereof; and,

FIG. 8 is an alternative perspective view including disclaimed environment of the vehicle antenna.

The dashed broken lines depict portions of the vehicle antenna or environment of the vehicle antenna which form no part of the claimed design. The dot dashed broken lines represent boundaries of the claimed vehicle antenna and form no part of the claimed design.

1 Claim, 8 Drawing Sheets(56)
